A. J. THERIAULT

GUIDE PLATE FOR WINDOW SCREENS

Filed Jan. 31, 1927

UNITED STATES PATENT OFFICE.

ADELARD J. THERIAULT, OF GRAND ANSE, NEW BRUNSWICK, CANADA

GUIDE PLATE FOR WINDOW SCREENS.

Application filed January 31, 1927. Serial No. 164,862.

This invention relates to window constructions in which one of the window sections are adapted to be moved up and down when desired. Attached to this movable section of the window is a foraminous screen, which is mounted on a suitable roller hereinafter explained in detail.

The object is to provide a means for automatically positioning the screen in the window opening when the movable section of the window is moved to cause an opening.

A further object is to provide a covering for the roller and screen, which covering will also act as a positioner and tightener for the drawn up portion of the foraminous screen.

With the foregoing and other objects in view, as will appear as the description proceeds, the invention consists in the novel construction, combination and arrangement of co-operating elements as hereinafter more specifically set forth, claimed and shown in the accompanying drawings forming a part of the present application, in which:

Fig. 1 is a plan view of a window showing the movable section moved to partially open position and the foraminous screen pulled up across such opening.

Fig. 2 is an end view showing the covering for the roller and the foraminous screening.

Fig. 3 is a sectional view showing the interior parts of the roller, part being broken away.

Fig. 4 is a sectional view showing a portion of the cover plate member and one end of the holder members.

Like numerals of reference designate corresponding parts throughout the different views.

This construction can be used in connection with practically any form of window wherein either the top or bottom sections are movable up and down. I have shown in Fig. 1 of the drawings, the screen attached to the lower section of the window, but it might be attached to the upper section by merely reversing the position of the same relative to the movable upper portion and attaching the screen to the upper part of the frame.

At each side of the window frame, I provide a channel guide 5 in which the opposite sides of the foraminous screen 6 will move up and down. These guides 5 will also act as a means for providing a tight closure be-

tween the screen 6 and the side of the window frame, so that the flies and other insects will not be able to find their way in between the screen and frame.

7 indicates a roller on which the screen is rolled when in its normal closed position. When the roller is being cut out of flat metal, lugs are provided at the opposite ends so that when the roller is shaped into a cylindrical shape, these lugs are positioned diagonally opposite each other and are bent towards the centre in the position as noted at 8. The inner ends of these lugs are provided with annular openings 9 registering opposite each other. Spaced a distance from the end, I provide a snugly fitting disc 10. Between the disc 10 and the lugs 8, I provide a tension roller 11 provided with a recoil spring 12. One end of this recoil spring is secured through the roller 11 as at 14 while the other end is secured to one of the lugs 8 as at 15. 16 is an end bracket provided with an inwardly formed portion adapted to operate in conjunction with the lugs 8, the end of 16 is an end bracket provided with an inwardly formed portion adapted to operate in conjunction with the lugs 8, the end of 60 the bearing pin from the roller 11 extends through an opening in this inwardly formed portion and is retained therein against turning.

The roller 7 is provided with two cylindrical sections one or both of which may telescope over a central cylindrical section 17. One of the end sections 7 may have a tight fitting with the central section 17, while the other end section may be moved relative thereto, so as to provide a wider or narrower roller to fit the desired opening. The central section 17 is provided with spaced indentations 18 into which a keeper 19 is adapted to engage, which keeper is formed from an integral lug cut from the end of the telescopic cylindrical section 7. It may be found that wider screens are desired and by having a roller of the type hereinbefore described, it will not be necessary to go to the extra expense of providing rollers, as a new screen the desired width can be easily attached to the roller when it is lengthened the desired length.

20 indicates a curved metal plate preferably having a rolled back front edge 21. This metal plate 20 is fitted between the end plates 16, which end plates are securely screwed to the window frame by the screws 22. The plate 16 carries inwardly directed pins 23, 24 and 25. The pin 25 extends inwardly and acts as a pivotal pin for the

lower rolled edge 26. 27 indicates a spring lapped around the pin 25 and having one end positioned against the pin 23, while the other presses against the curved metal plate 5 20. This spring 27 presses the plate 20 so that its upper portion will normally rest against the pins 24 in the opposite end plates 16. The rolled edge 21 will protrude outwardly a sufficient distance so as to align 10 the pulled out portion of the screen 6 with the path of travel of the movable section of the window. The curved plate 20 will form a neat cover fitted over the screen when rolled up on the roller either on the sill or on 15 the upper portion of the frame.

The foregoing specification and annexed drawings disclose the preferred embodiment of my invention, but it is to be understood that minor changes may be resorted to in

the commercial adaptation of my invention 20 without departing from the scope of the invention as hereinafter claimed.

What I claim as new is:

In combination with a roller screen mounted in end plates secured to a window 25 sill, the end of said screen having contact with a movable sash frame, a guide plate for directing said screen to and from the path of travel of said frame; said plate being pivotally connected to said end plates; 30 means for pressing said plate towards said screen and a means carried by each of said end plates to limit the downward movement of said plate under said tension.

In testimony whereof, I affix my signature. 35

ADELARD J. THERIAULT.
